UNITED STATES PATENT OFFICE.

FRANK PATAK, OF JERSEY CITY, NEW JERSEY.

PAPER-FEEDING MACHINE.

1,366,484.

Specification of Letters Patent. Patented Jan. 25, 1921.

Application filed January 28, 1920. Serial No. 354,698.

To all whom it may concern:

Be it known that I, FRANK PATAK, a citizen of the United States, and a resident of Jersey City, in the county of Hudson and 5 State of New Jersey, have invented certain new and useful Improvements in Paper-Feeding Machines, of which the following is a specification.

The present invention relates to paper 10 feeding machines, and more particularly to separators, that is to say to means for removing an individual sheet from its position in a stack.

In one type of these machines, spring- 15 pressed feeding fingers are employed, said fingers being pivoted to a support and separating the sheets by being rocked and moved back and forth in relation to the stack. Serious difficulties have been experienced 20 with these feeding means for the reason that the springs, acting upon the feeding fingers, are apt to break and are then carried forward to the printing mechanism, causing injury, etc., to the same.

25 The main object of the invention is to provide a simple and efficient protecting means, which prevents broken springs from being carried forward toward the printing mechanism.

30 Another object of the invention is to so construct the spring protecting means that it can be conveniently mounted on already existing structures, without necessitating any change whatever in the construction of 35 the feeding device.

With these and other objects in view, which will more fully appear as the nature of the invention is better understood, the same consists in the combination, arrangement and construction of parts hereinafter 40 described, pointed out in the appended claim and illustrated in the accompanying drawings, it being understood that many changes may be made in the size and proportion of the several parts and details of 45 construction within the scope of the appended claim, without departing from the spirit or sacrificing any of the advantages of the invention.

50 One of the many possible embodiments of the invention is illustrated in the accompanying drawings, in which:—

Figure 1 is a side elevation of a feeding mechanism provided with spring protecting means constructed in accordance with the present invention; Fig. 2 is a front ele-

vation thereof; Fig. 3 is a plan view of the same, partly in section; and Fig. 4 is a section taken on line 4—4 of Fig. 3, on a larger scale.

In the drawings, the numeral 10 indicates 60 a rubber roll, mounted on a spindle 11, the latter being fixedly attached to a supporting arm 12. This arm is pivoted on a stud 13, carried by a frame 14. Around the stud 65 is coiled a tension spring 15, one end thereof bearing against a pin 16 on the arm 12, and its other end engaging a pin 17 on a nut 18, by means of which the tension of the spring 70 may be varied. The tension spring 70 operates to throw the roll support and roll downward, so as to bring the roll into contact with the top sheet of the pile. A mechanism 19 of any suitable construction is provided, to limit the downward movement 75 of the roll.

The spring 15 is inclosed by a housing 20, made of two sections, denoted by the numerals 21 and 22, said sections being provided with apertures 23 and 24, through 80 which the pins 16 and 17, respectively, extend. The section 21 of the housing is fixed by the pin 16 to the arm 12, and the section 22 is fixed by the pin 17 to the tension nut 18. These two sections are thus movable in 85 relation to each other and do not interfere with the proper operation of the device.

When the parts are assembled, as shown in the several figures of the drawings, the tension of the spring may be adjusted without dismounting the housing from the stud 90 13. All that is necessary is to disengage the cotter pin 25 from the notches 26 in the outer face of the nut, and turn the latter with the housing section 22 into the proper 95 position, and then seat the cotter pin in those notches 26, which register with the hole 27 in the stud 13.

In operation, the frame 14, with the roll support 12 thereon, is moved back and 100 forth and the roll support rocked on its stud 13 in the well-known manner, to feed the sheets, one after the other, from the stack. The housing section 21 partakes of the rocking motion of the roll support. The housing 105 incloses completely the spring, so that, in case the latter breaks, it will be prevented from dropping onto the paper stack.

What I claim is:—

In a sheet feeding device, the combination 110 with a movable frame provided with a stud, of a roll support pivoted to said stud, a roll

carried by said support, a tension spring on said stud, an adjusting nut on said stud, one end of said tension spring being in engagement with said roll support and the other end with said nut, and a housing on said stud completely inclosing said spring, said housing being made of two sections, one of

which is fixed to said roll support and the other one to said adjusting nut.

Signed at New York, in the county of 10
New York and State of New York, this 15th
day of January, 1920.

FRANK PATAK.
